UNITED STATES PATENT OFFICE.

NATHANIEL BOIS, OF SAN FRANCISCO, CALIFORNIA.

INTERLOCKING STAIR-FORM.

1,304,533.

Specification of Letters Patent. Patented May 27, 1919.

Application filed December 24, 1917. Serial No. 208,990.

To all whom it may concern:

Be it known that I, NATHANIEL Bois, a citizen of the United States, residing in the city and county of San Francisco and State 5 of California, have invented a new and useful Improvement in Interlocking Stair-Forms, of which the following is a specification.

My invention relates to improvements on 10 interlocking stair forms of the type disclosed in the United States Patent No. 1,244,021 issued to me on the 23rd day of October, 1917, and consists in the elimination of certain parts of the above referred 15 to type without a corresponding omission of function; and the objects of the present invention are:

First, to provide an improved stair form of improved construction requiring less material;

Second, to provide an improved stair form wherein a simplified construction produces a rigid and efficient form for the support of slabs or concrete filling; and

Third, to provide an improved stair form of the type described adapted to provide a form for concrete stairs wherein the nosing of said concrete may extend above the metal nosing of the form.

I accomplish these several features by means of the device disclosed in the drawings forming a part of the present specification wherein like characters of reference are used to designate similar parts throughout the said specification and drawings, and in which—

Figure 1 is a perspective view partly in section disclosing the improved stair form;

Fig. 2 is a vertical section view on an enlarged scale of a portion of a stair-case disclosing the invention more in detail;

Fig. 3 is a broken front elevation of Fig. 2; and

Fig. 4 is a vertical sectional view of a modified form of tread.

Referring to the drawings the numeral 1 is used to designate in general a stair form consisting of a riser 2 and a tread 3.

The tread 3 is provided with an upwardly 50 extending flange or nosing 4 the purpose of which will hereinafter be more fully described. The riser 2 is provided at the upper end thereof with a rearwardly facing channel comprising a bottom wall 6, a forward side wall 7, and a downwardly and rearwardly inclined top wall 8.

In assembling the stair forms the upwardly extending nosing 4 of one tread is inserted and interlocked with the adjacent stair form by inserting the said nosing 4 60 into the channel on the riser 2 so that the upper end or edge of said nosing 4 will rest tightly within the angle formed by the inclined top wall 8 and the forward side wall 7 of the said channel with the forward bottom surface of the tread 3 on one stair form resting on and in continuous contact with the top of the bottom wall 6 of the channel on the riser 2.

The ends of the riser 2 and tread 3 are inserted into a form so as to become embedded within concrete stringers 12 formed on each side of the stair forms 1, said stringers 12 being provided with the usual reinforcing rods 14 to which the stair forms are tied by 75 means of twisted wire eyelets 16 as disclosed in Figs. 1 and 3 of the drawings.

After a sufficient number of stair forms have been interlocked to form a stairway, concrete treads 9, of greater depth than the 80 height of the nosing 4, are formed upon the treads 3 so as to provide a concrete nosing 10 above the metal channel interlocking the nosing 4. Owing to the rearward and downward inclination of the top wall 8 of the 85 channel formed on each riser 2 the concrete nosing 10 diminishes in sectional area toward the forward end of the stair thereby providing a concrete nosing 10 of superior strength and one not likely to crack or break 90 off through usage.

The concrete nosing 10 extending above the metal nosing and channel of the stair form also provides a means for protecting the metal nosing of the stair from excessive 95 wear.

In the modified form of the invention as disclosed in Fig. 4 of the drawings I have provided an offset 17 so as to raise the greater rear portion of the tread 3 to the 100 same plane as the upper surface of the top of the channel formed on the riser 2 thereby providing a support for a slab 18 of slate, marble or other suitable material.

This offset 17 forms a pocket 19 within 105 which may be poured concrete to securely retain the interlocked nosing and channel as disclosed in Fig. 4 of the drawings.

It is obvious from the foregoing that I have provided an improved and simplified 110 construction for interlocking stair forms wherein a saving of weight and material is

effect without diminishing the rigidity or efficiency of the interlocked forms.

Having thus described my invention what I claim as new and desire to secure by Letters Patent is—

1. The combination with a stair form having a tread, a riser connected thereto, and a rearwardly facing channel formed on the upper edge, said channel comprising a bottom wall, a downwardly inclined top wall, and a forward side wall, of a second stair form having a tread and an upwardly extending nosing extending into the channel and between the side wall and inclined top wall on the riser to interlock said riser and nosing.

2. The combination with a stair form having a tread, a riser connected thereto, and a rearwardly facing channel formed on the upper edge of said riser, said channel comprising a bottom wall, a downwardly inclined top wall and a forward side wall, of a second stair form having a tread and an upwardly extending nosing formed on the forward edge of said tread and extending

into the channel on the riser and in contact with the bottom wall thereof and the upwardly extending nosing of the tread is held in contact with the forward wall of the channel on the riser by the inclined top wall of said channel to interlock said riser and tread.

3. The combination with a stair form having a tread and riser and nosing formed on the front edge of said tread, of a second stair form having a similar tread, a riser connected thereto, and a rearwardly facing channel formed on the top of the riser, said riser comprising a bottom wall, a forward side wall and a top rearwardly and downwardly inclined top wall, said channel engaging the bottom of the forward edge of the tread and the forward wall and inclined top wall engaging the upwardly extending nosing on the tread to interlock said nosing and riser.

In witness whereof I hereunto set my signature.

NATHANIEL BOIS.
